HOBBYHORSE

George B. Naegle, San Jose, Calif.

Application April 17, 1940, Serial No. 330,076

3 Claims. (Cl. 280—1.15)

The present invention relates particularly to that type of hobbyhorse designed to simulate the action of a living horse in action.

It is one object of the present invention to provide a hobbyhorse that is mounted on wheels and propelled by the rider, and one in which the propelling forces are applied, in a large measure, by body movements of the rider.

It is another object to provide a device of the character indicated wherein complete action is secured through changing application of various forces including the shifting of the center of gravity of the rider, pressure applied through the legs of the rider, and pulling forces applied 10 through his arms, and one in which the application of these various forces results in the coordinate movement of the body, legs and head of that portion representing a horse.

It is also an object to provide a device of the character indicated that will bring into play the entire muscular system of the rider and create in his mind the illusion of riding a living horse.

Finally, it is an object to provide a device having the characteristics above set forth that will be economical to manufacture, simple in form and construction, strong, durable, and highly efficient in its practical application.

In the drawing:

Figure 1 is a side elevation of a device embodying my invention, with parts broken away.

Figure 2 is a sectional view on line 2—2 of Figure 1.

Figure 3 is a sectional view on line 3—3 of Figure 1.

Figure 4 is a diagrammatic illustration indicating the extreme relative positions of the several moving parts, positions through which the parts pass when the device is in operation.

The device consists of two main parts, a wheeled chassis and a figure simulating an animal, in this instance a horse.

The chassis comprises a frame 1 having an elevated and horizontal front portion 2 fitted with a vertical tubular portion 3 in which is mounted the front steering wheel structure 4 with its wheel 5.

The rear end of the frame 1 is formed into an oval and horizontally disposed part as indicated at 6, and in this part 6 is journaled a crank-shaft 7 as at 8, the shaft having wheels as 9—9 mounted thereon. The shaft 7 is formed into three cranks as 7a and 7b—7b, lying in a common plane as shown. Extending transversely through frame 1 at a point adjacent part 4, and in the present

instance at a height substantially one-half the height of part 4, is a pivot pin 10.

The figure mounted upon the chassis comprises a body 11, a head 12, a pair of front legs 13, and a pair of rear legs as 14, and all of these parts are assembled in the following manner.

The rear legs 14 are pivotally mounted on the body 11 at 15, and also upon the crank portions 7b—7b as at 16.

The front legs 13 are pivotally mounted on the body 11 at 17, and upon the pivot pin 10 at 18, a point intermediate the body 11 and the extremity of the leg.

The body 11 is built up of three flat boards, as 11a, 11b, 11c, the boards 11a and 11c being 15 mounted upon and spaced by the part 11b, and the part 11b filling in only the rear part of the body so that a free and open channel 19 is provided between the forward portions of the side parts 11a and 11c.

The head 12 is mounted upon a bar 20 that is in turn pivotally mounted on the parts 11a—11b and in the channel 19 as at 21. Each pivot 21 is seated in the adjacent body portion but does not pass therethrough, so that they in no way interfere with the free pivotal movement of the bar 20 on pivot 21. The position of pivot 21 may be varied to secure a desired relative movement between the head and body, but in any case is eccentric to the pivotal mounting 17.

The end of the bar remote from pivot 17 is journaled on crank portion 7a and consequently lies in the vertical plane of body 11. A foot rest 23 passes horizontally through the bar 20 just below body 11 for the purpose hereinafter more fully set forth.

In Figure 1 the body 11 is shown in a substantially horizontal position with the cranks 7a—7b lying in a horizontal plane, the extremities of legs 14 being rearwardly of the axis of shaft 7 and the lower end of bar 20 being forwardly of the said axis. In the present arrangement the pivotal point 21 is forwardly of the pivotal points 17.

A child sitting on the body 11 with its feet on rest 23 and pulling on reins 23a attached to the handle 24, will throw its weight forwardly and exert a downward force on rest 23 as indicated by arrow 25. This action operates to move the several parts into the position indicated in solid lines in the diagram because the downward thrust of bar 20 rotates the shaft 7 in the direction indicated by arrow 26, thereby elevating the rear legs 14 and the rear end of body 11. Since the pivotal point 21 is located forwardly and upwardly rel-

20

ative to pivotal point 17, the above described upward tilting of the body and angularly downward and rearward movement of bar 20 operates to rotate pivotal point 21 a distance about the 5 pivotal point 17 because the same tilting movement causes the pivotal point 17 to swing about the pivotal point 10 as indicated by arrow 27. The readjustment of the several pivotal points then, not only moves the body 11 into a forwardly tilting position but also swings the head 12 backwardly because it is an integral part of the bar 20 and the inclination of the said bar 20 is increased.

Now if the child leans backwardly so that its 15 weight is applied to the rearward portion of the body at 28 and removed from the bar 20 at 29, while still pulling on reins 23, the force applied at 28 will, through the medium of legs 14, rotate the axle 7 in the direction 26 and cause the 20 several parts to move through the position shown in Figure 1 to the position shown in dotted lines in the diagram, thereby completing the cycle of operation. Since the front legs 13 are pivotally mounted at 18, the movement of pivotal point 15 25 to the new position 15a swings the pivotal point 17 to point 17a, and the combined movement of body 11 and front legs 13 and bar 20 moves the point 21 to 21a thereby moving the head into position 12a.

30 It may now be seen that the continued operation of the device not only drives the vehicle forwardly, but also imparts a regular sequence of movements to the several parts of the body that simulate the action of an animal in motion.

35 The part 6 of frame 1 is extended a distance beyond the rear wheels 9 as at 29 so that when the weight if the child is thrown backwardly far enough the front wheel 5 may be pulled off of the ground and the said part 29 caused to contact the ground and act as a brake.

Although but one specific embodiment of the invention has been herein illustrated and described, it will be understood that various alterations in the details of construction and mode of 45 assembly may be made without departing from the scope of the invention as indicated in the appended claims.

I claim:

1. A device of the character described comprising, a wheeled chassis including a front steering 50

wheel and a pair of rear drive wheels and a crank shaft connecting said drive wheels, a body portion simulating an animal mounted on the chassis, said body portion including a body having front and rear legs and head pivotally mounted thereon, the foot extremities of the rear legs being journaled on the crank shaft, and the front legs being pivotally mounted on the chassis at a point intermediate their length, and a bar connecting the head and crank whereby an angular downward pressure on the bar will turn 10 the crank and actuate several pivoted members.

2. A device of the character described comprising, a chassis having a front steering wheel, a pair of rear driving wheels, and a crank shaft 15 connecting the drive wheels, said shaft having oppositely disposed cranks lying in the same plane, and a body mounted on the chassis through the medium of front and rear legs pivoted on the body, the front legs also being pivoted on the 20 chassis at a point intermediate their length and the rear legs also being journaled on the crank shaft at their foot extremities, and a head member pivoted on the body in offset relation to the pivotal mounting of the front legs and having 25 a part extending angularly downwardly and rearwardly and journaled on the crank shaft in opposed relation to the mounting of the rear legs.

3. A device of the character described comprising, a chassis having a front steering wheel, a pair of rear driving wheels, and a crank shaft 30 connecting the drive wheels, said shaft having oppositely disposed cranks lying in the same plane, and a body mounted on the chassis through the medium of front and rear legs pivoted on the body, the front legs also being pivoted on the chassis at a point intermediate their length and the rear legs also being journaled on the crank shaft at their foot extremities, and a head member pivoted on the body and in the plane 35 thereof at a point disposed forwardly and upwardly with relation to the pivotal mounting of the front legs and having a part extending downwardly and rearwardly and journaled on the 40 crank shaft in opposed relation to the mounting of the rear legs, and a foot rest mounted on the last mentioned part at a point immediately below the body.

GEORGE B. NAEGLE. 50
